UNITED STATES PATENT OFFICE.

STANLEY W. MIDGLEY, OF CHICAGO, ILLINOIS, ASSIGNOR TO THE CURTAIN SUPPLY COMPANY, OF CHICAGO, ILLINOIS, A CORPORATION OF ILLINOIS.

CAR-VESTIBULE DIAPHRAGM.

1,095,909.

Specification of Letters Patent.

Patented May 5, 1914.

Application filed April 17, 1912. Serial No. 691,347.

To all whom it may concern:

Be it known that I, STANLEY W. MIDGLEY, a citizen of the United States, residing at Chicago, in the county of Cook and State 5 of Illinois, have invented certain new and useful Improvements in Car-Vestibule Diaphragms, of which the following is a specification.

In connection with the use and employment 10 of the accordion-shaped collapsible and extensible diaphragms used in association with the vestibules of railway cars, it is sometimes desirable or necessary to be able to tip or tilt the outer face plate an appreciable amount to permit or facilitate the removal of the buffer mechanism or portions thereof. Heretofore, one way to accomplish this result has been to joint or hinge together the parts of the fastening strap holding 15 the inner portion of the diaphragm to the end wall of the car vestibule, so that by detaching or unfastening parts of the fastening strips they may be turned on such hinges or joints, permitting the tipping or 20 tilting of the diaphragm for the purpose indicated. Such a construction has certain objectionable features, and the object of the present invention is to make a car diaphragm of this general character by which 25 such result can be more readily and easily secured, and in order to accomplish this I 30 separably or detachably connect certain of the plaits of the accordion diaphragm so as to render the same capable of being opened 35 or separated without destruction or injury of the parts to permit the necessary or desirable inclinations of the outer face plate.

In order that a full and complete understanding 40 of this invention may be had, I have illustrated a desirable and preferred embodiment of the same in the accompanying drawings forming a part of this specification, and to which reference should be had in connection with the following detailed description.

In this drawing: Figure 1 is a longitudinal vertical section through the end portion of a car; Fig. 2 is a cross-section on a vertical plane passing through the accordion dia- 50 phragm; Fig. 3 is an enlarged horizontal cross-section on line 3—3 of Fig. 2, and Fig.

4 illustrates in enlarged section the various parts forming the separable or detachable connection between the two adjacent fabric strips forming one of the plaits of one of the 55 legs of the diaphragm.

In the drawings, the end-wall or post of the car vestibule is supplied with the reference character 10, and to one face of such post is fastened, by means of a metallic strip 60 11, one end of an inverted U-shaped accordion diaphragm composed of a plurality of inverted U-shaped strips of fabric 12, 12, fastened together along their opposite longitudinal edges to complete the accordion 65 structure, such edges being covered by suitable binding strips 13. At its center, however, each leg of the diaphragm, for a portion at least, of its length from the bottom upward instead of being stitched or riveted, 70 is provided with a separable, releasable or detachable fastening consisting of a plurality of round studs 14, each having a substantially rectangular shank 15 passing through a hole in the edge portion of one of 75 the strips of fabric 12 and held in place by a pair of washers 16 and 17 having apertures conforming to the cross-section of the shank 15, each of such washers having one or more prongs to prevent it from turning relatively 80 to the fabric. This pin, or rod 14 at one end has an enlarged head 18, and between the washer 17 and the fabric 12 is fastened by means of these pins or rods, a cover strip 19 preferably of rawhide, or similar rain and 85 weather-proof material. The next adjacent fabric strip 12 of the diaphragm is provided with a plurality of metallic eyelets 20 in register with the pins 14, and the free edge portion of the cover strip 19 is also supplied 90 with metallic eyelets 21. When the plait or seam is closed, the strips 12, 12, are brought together, the pins 14 extending through the eyelets 20 and also through the eyelets 21 of the cover strip 19, these parts being held in 95 this closed or assembled relation by means of cotter pins 22 extended through holes 23 in the pins 14. As is clearly shown in the drawings, these detachable connections or separable fastenings extend upwardly for 100 about two-thirds of the length of the legs of the diaphragm, which is sufficient under or

ordinary circumstances to permit the necessary inclination of the face plate, as is indicated in dotted lines in Fig. 1, to remove either wholly or in part, the buffer mechanism of the platform. 50

Under ordinary circumstances, all of the plaits of the accordion structure are closed, the protecting or covering strips 19 closing the joints between the adjacent fabric dia- 10 phragm strips 12, 12, all of the parts being held in proper assembled condition by the cotter pins 22. When it is desired to tip the face plate, the cotter pins 22 are removed from their holes 23, the strips 19 and 15 the eyelets 21 being removed from the cylindrical portions 14 of the pins, which then permits the separation of the adjacent fabric strips 12, 12. In other words, two opposite plaits on the two legs of the dia- 20 phragm are opened up for a portion of their length. This, of course, permits a tilting of the face plate 24 into the dotted line position shown in Fig. 1. After the buffer mechanism has been replaced or repaired, 25 then the parts of the diaphragm are again assembled, the cotter pins 22 holding them together in the desired relation. Although I have shown these protecting covers 19 and 30 separable joints or seams at the inner edges of the legs of the diaphragms, they could, of course, be at the outer edges if found to be preferable. By employing a construction of this character, no hinge or other similar joint is necessary in the strip or strips 11 se- 35 curing the diaphragm to the posts or end wall of the vestibule, the partial detaching occurring in the diaphragm proper as distinguished from its connection with the car vestibule. 40

Although in this specification one partic- ular embodiment of the invention is illus- trated and described in detail, it is not to be understood or inferred that the invention is limited and restricted to this particular 45 form and style of structure, because many minor mechanical changes could be made in the features herein set forth, without depar- ture from this invention and without the

sacrifice of any of its substantial benefits and advantages. 50

What I claim is:

1. A car vestibule diaphragm having in each leg an open plait, and means to releasably connect the adjacent portions of the plait, whereby the plait may be closed or 55 opened at will to permit the tilting of the face plate without injury to the parts, substantially as described.

2. A car vestibule diaphragm of accordion form having in each leg an open plait com- 60 posed of two pieces of fabric separable for at least a portion of their length, and releasable means to detachably connect the two pieces, whereby the plait may be closed or opened at will to permit tilting of the face 65 plate without injury to the parts, substantially as described.

3. As an article of manufacture, a car ves- 70 tibule diaphragm of accordion form, each leg of the diaphragm having a plait com- posed of two pieces of fabric, a plurality of pins fastened to one of said pieces of fabric having apertures through which said pins are adapted to extend, and means associated 75 with said pins to detachably fasten together the pieces of fabric for at least a portion of their length, substantially as described.

4. As an article of manufacture, a car ves- 80 tibule diaphragm of accordion form, each leg of the diaphragm having a plait com- posed of two pieces of fabric, pins fastened to one of said pieces of fabric, the companion piece of fabric having apertures through which said pins are adapted to project, a cover-strip fastened to one of said 85 pieces of fabric and adapted to fold over the other piece, and means associated with said pins and cover strip to detachably fasten together said pieces of fabric and hold the cover-strip in position, substantially as de- 90 scribed.

STANLEY W. MIDGLEY.
